UNITED STATES PATENT OFFICE.

ARTHUR DÉSIRÉ BOUDET, OF PARIS, FRANCE, ASSIGNOR TO JULES LEON VIMONT, OF PARIS, FRANCE.

SHIRT-BAND STIFFENER.

SPECIFICATION forming part of Letters Patent No. 700,013, dated May 13, 1902.

Application filed February 15, 1902. Serial No. 94,152. (No model.)

To all whom it may concern:

Be it known that I, ARTHUR DÉSIRÉ BOUDET, a citizen of the French Republic, residing in Paris, France, have invented certain new and 5 useful Improvements in Shirt-Band Stiffeners, of which the following is a specification.

This invention has for its object a detachable attachment of celluloid, metal, or any other suitable supple and resistant material 10 for stiffening the neckbands or wristbands of soft shirts, such as shirts of flannel or silk, Oxford shirts, Jersey shirts, and the like. The said attachment is in two parts jointed or hinged together by means of an eyelet or 15 any other suitable joint, so as to facilitate its introduction into the neckband or wristband through an opening formed for this purpose in these parts.

The following description, referring to the 20 accompanying drawings, will clearly explain the invention as applied to the neckband of a soft shirt.

Figure 1 shows the neckband of the soft shirt without my attachment. Fig. 2 shows 25 the neckband of the shirt stiffened like the starched neckband of a linen shirt by means of the attachment. Fig. 3 is a section through the buttonhole of the neckband without the attachment. Fig. 4 is a similar section showing 30 the attachment placed in the neckband. Figs. 5 and 6 show a partial plan view and a section, respectively, of the said attachment. Fig. 7 is a plan view to a reduced scale of the attachment.

35 The detachable attachment comprises two lengths or sections *a* and *b*, which are thin and the breadth of which decreases toward the end opposite the joint or hinge. The right-hand length *a* is placed over the left-hand length *b* and is jointed to the same by means of an eyelet *c*, of metal, which passes through both parts. Below the eyelet *c* upon the length *a* is fitted a stud or button, preferably a double button *d*, of celluloid or metal, 40 which serves for receiving the collar when

the attachment is placed in position in the neckband. The metal eyelet can be coated externally with celluloid *g*, which protects it against the action of the atmosphere and enables the attachment to be cleaned without 50 injuriously affecting the metal.

At the back the neckband of the soft shirt is formed under the buttonhole with a slit *e*, similar to that made in ordinary shirts, but larger and through which the attachment is 55 introduced. To this end two lengths *a* and *b* can be inclined to one another, so that they form an acute angle, the two lengths being then introduced into the slit on either side of the buttonhole *f*. The attachment is then 60 pushed in, so as to cause the two lengths to pass into the annular space formed between the double thickness of the neckband. When this has been done, it is only necessary to pass the stud or button *d* through the buttonhole, and the neckband is then ready to 65 receive the collar. The ribbon or the like *h*, of linen or cotton, under which the tie is passed to hold it in position can, if necessary, be attached to the stud, so as to prevent the 70 part of the neckband containing the button-hole from rising under a pull upon the said neckband.

I claim—

1. A stiffener for a shirt-band consisting of 75 two sections of thin, resilient material hinged together at their ends, said stiffener being provided, adjacent to the hinge, with a stud.

2. A stiffener for a shirt-band consisting of two similar sections of thin, resilient material 80 hinged together at their overlapping ends and one of said sections having a stud attached to it below and adjacent to the hinge.

In witness whereof I have hereunto signed my name this 31st day of January, 1902, in 85 the presence of two subscribing witnesses.

ARTHUR DÉSIRÉ BOUDET.
